UNITED STATES PATENT OFFICE

2,384,734

MIXTURES OF AZO DYESTUFFS

Friedrich Felix and Alphonse Heckendorf, Basel,
Switzerland, assignors to the firm Society of
Chemical Industry in Basle, Basel, Switzerland

No Drawing. Application September 11, 1943,
Serial No. 502,027. In Switzerland October 2,
1942

5 Claims. (Cl. 8—26)

Acid sulfuric acid esters of para-N-alkylamino-
azo-dyestuffs hydroxylated in the N-alkyl groups
have become known by British Patent No. 181,-
750. It can be gathered from the data of this
patent that it is possible to produce compounds
corresponding to the general formulas.

and

wherein R_1 and R_2 stand for aromatic nuclei of
the benzene series. Such products are to be used
primarily as silk or wool dyestuffs.

By British Patent No. 237,739 it has further
become known that the acid sulfuric acid esters
of the para-aminoazo-dyestuffs which correspond
to the type

wherein R_1 and R_2 stand mostly also for benzene
nuclei, can be used successfully for dyeing cellulose
esters, especially acetate rayon. Recently,
quite a series of azo-dyestuffs for cellulose esters
and ethers have become known which all correspond
to the just indicated type.

However, the manufacture of such dyestuffs
requires the production of unsymmetrical-N-di-
alkylated aromatic amines, which entails the
manufacture of pure N-monoalkylated amines,
thus making a special operation necessary. In
many cases, however, no requirement exists for
the symmetrical N-dialkylated amines which are
always formed thereby. When trying to circum-
vent this complication by producing and using,
respectively, para-aminoazo-dyestuffs of the type

(wherein R_1 and R_2 have the above given signifi-
cance), it is found that such dyestuffs are not
suitable for dyeing acetate rayon, as they have a
much too weak affinity for such materials when
dyed from their aqueous solutions.

It has now been found that the para-amino-
azo-dyestuffs of the general formula

5 wherein R_1 and R_2 have the above given signifi-
cance, R_1 carrying a nitro group in para-position
to the $-\text{N}=\text{N}-$ group and R_2 carrying the
10 $-\text{N}=\text{N}-$ group and the

15 atom in paraposition to one another, which
dyestuffs have been partially converted into
acid sulfuric acid esters, are products which,
especially in the form of their salts, for ex-
ample in the form of their alkali or ammonium
salts, are distinguished from the non-esterified
20 dyestuffs by their good solubility in water and
from the completely esterified products by their
excellent affinity for cellulose esters and ethers.
They dye these textile materials, according to
their constitution, preferably red to brown, violet
25 and blue shades. The new dyestuffs may also be
used for other purposes, for example for dyeing
synthetic fibers of animal character, such as
superpolyamides or superpolyurethanes.

For producing the new products one may start
30 quite generally from primary aromatic amines of
the general formula

35 wherein R represents an aromatic nucleus of the
benzene series which is capable of coupling with
diazo compounds in 4-position to the

40 and from unsulfonated diazo compounds of the
benzene series nitrated in 4-position to the diazo
group, the

45 50 either before or after coupling to the azo-dyestuff,
being converted with suitable esterifying agents,
such as sulfuric acid, chlorosulfonic acid, etc., into

an acid sulfuric acid ester in such a manner, that at least one, but not both OH-groups are esterified. It has been found that the esterification may be effected in a surprising manner in stages, the most favorable conditions regarding affinity and solubility being different depending on the nature of the azo-dyestuff. Whereas, for example, certain azo-dyestuffs behave best in the form of their monoesters, a higher degree of esterification is appropriate in other products, so that for example up to 1½ OH-groups must be esterified.

The new dyestuffs are therefore derived from preferably symmetrical N-di-hydroxyalkylated aromatic amines, such as N-di-hydroxyethyl-aminobenzene, 3-methyl - N - di-hydroxyethyl-aminobenzene, 3-chloro - N - di-hydroxyethyl-aminobenzene, 3-methoxy-N-di-hydroxyethyl-aminobenzene, 2-methoxy- N - di-hydroxyethyl-aminobenzene, 2-methoxy - 5 - methyl-N-di-hydroxyethyl-aminobenzene, 2:5-dimethoxy- or 2:5-diethoxy-N-di-hydroxyethyl-aminobenzene, further from the corresponding N-di-hydroxy-n-propyl, N-di-hydroxy-n-butyl, N-di-hydroxy-n-amyl compounds, and so forth. The alkyl radicals may also be branched (for example represent isobutyl radicals) and contain further substituents, for example halogen atoms.

As diazotizing components there may be used compounds such as 1-amino-4-nitrobenzene, 1-amino-2:4-dinitrobenzene, 1-amino-2-methoxy-4-nitrobenzene, 1-amino-2-methyl-4-nitrobenzene, 1-amino-2-chloro-4-nitrobenzene, 1-amino-2:6-dichloro-4-nitrobenzene, 1-amino-2:4-dinitro-6-chlorobenzene, 1-amino-2-cyano-4-nitrobenzene, 1-amino-2-cyano-6-chloro-4-nitrobenzene, 1-amino-2-cyano-4:6-dinitrobenzene, 1-amino-2-methylsulfone-4-nitrobenzene, 1-amino-2-methylsulfone-4:6-dinitrobenzene, and the like.

The new products represent therefore mixtures of dyestuffs which in the free form correspond to the general formulas

wherein the proportion of the monoester (I) to the diester (II) is such that in 100 parts of dyestuff mixture the content of monoester (I) amounts to at least 50 per cent. and the content of diester (II) amounts to not more than 25 per cent., in which formulas R₁ and R₂ stand for aromatic nuclei of the benzene series which are free from hydroxyl, carboxyl and sulfonic acid groups, R₁ containing a nitro group standing in para-position to the —N=N— group, and the —N=N— and the

groups in R₂ standing in 1:4-position to each other.

The following examples illustrate the invention, but are not to be regarded as limiting it in any way, the parts being by weight:

Example 1

195 parts of 3-methyl-N-di-hydroxyethyl-aminobenzene are dissolved in 1000 parts by volume of carbon tetrachloride while slightly heating to 40-45° C. To this solution are gradually added 116-150 parts of chlorosulfonic acid from a dropping funnel, while stirring the solution, the operation being conducted in a reflux apparatus. The reaction occurs instantaneously with evolution of gaseous hydrochloric acid and heat. As the esterification advances, the reaction product is precipitated as a viscous mass from the carbon tetrachloride solution. When the whole quantity of the chlorosulfonic acid is introduced, the solution is allowed to cool, while stirring, the mixture which can now be stirred only with difficulty is mixed with 2000 parts of warm water and stirring is continued until all is dissolved. The aqueous solution of the ester is then separated from the carbon tetrachloride in a separating funnel and coupling is effected by allowing the diazo solution obtained as described below from 1-amino-2-cyano-4-nitrobenzene to flow to the solution in the presence of ice. The diazo solution is obtained by introducing 70 parts of sodium nitrite into 1000 parts of concentrated sulfuric acid and then 163 parts of 1-amino-2-cyano-4-nitrobenzene into the nitrosyl sulfuric acid thus obtained. When coupling is complete, the mineral acid in excess is made neutral to congo by addition of about 1300 parts of sodium hydroxide solution of 30 per cent. strength and the dyestuff suspension is neutralized completely with some ammonia. The dyestuff is salted out by addition of common salt, suction-filtered and washed with a dilute common salt solution. After drying there is obtained a dark powder which dissolves readily in water and dyes acetate rayon from the neutral bath in the presence of sodium sulfate violet shades. A similar dyestuff which dyes acetate rayon red-brown shades is obtained when using in this example as diazo component 207 parts of 1-amino-2:6-dichloro-4-nitrobenzene.

Example 2

The operation is conducted as in Example 1. When the esterification of the 3-methyl-N-di-hydroxyethyl-aminobenzene with chlorosulfonic acid is complete and after cooling the mixture, the carbon tetrachloride in excess is decanted and remains which are still adhering to the mass are removed in a vacuum. The residue thus obtained is then dissolved in 3000 parts by volume of methanol, the solution is cooled to -10° C. by external cooling and coupled by adding the diazo solution from 1-amino-2-cyano-4:6-dinitrobenzene drop by drop. The diazo solution is obtained by introducing 70 parts of sodium nitrite in 1000 parts of concentrated sulfuric acid and then 208 parts of 1-amino-2-cyano-4:6-dinitrobenzene into the nitrosyl sulfuric acid thus obtained. When coupling is complete, the methylalcoholic dyestuff suspension is poured into ice water, the dyestuff is suction-filtered, stirred with a little water, neutralized with ammonia and sucked off. When dry there is obtained a dark powder which dissolves readily in water and dyes acetate rayon from the neutral bath in the presence of sodium sulfate blue shades.

Example 3

12.8 parts of chlorosulfonic acid are gradually introduced into the solution of 33 parts of the water-insoluble azo-dyestuff which is obtained by coupling N-di-hydroxyethyl-aminobenzene with

the diazo compound of 1-amino-4-nitrobenzene, in 200 parts by volume of tetra-chloroethane, while heating and thoroughly stirring, the temperature being allowed to rise slowly to 70° C. Stirring is continued until the mixture is cold, the 5 dyestuff is sucked off and dried in a vacuum. The dyestuff powder is then stirred in some water and neutralized with ammonia. After suction-filtering and drying there is obtained a red powder which dissolves readily in water and dyes acetate 10 rayon from a neutral bath in the presence of sodium sulfate scarlet red shades.

Further dyestuffs can be produced according to the above prescriptions—if necessary modified appropriately—from the diazotizing and coupling components mentioned in the introduction. From the following list can be gathered the composition of such dyestuffs as well as the shade of the dyeings which they yield on acetate rayon:

1 part of the dyestuff of the first paragraph of Example 1 is dissolved in 3000 parts of water. The dye-bath is mixed with 40 parts of crystallized sodium sulfate and 100 parts of acetate rayon yarn are treated in this bath for 1 hour at 80° C.. After rinsing and drying there is obtained an acetate rayon which is dyed pure violet shades.

Example 4

1.2 parts of the dyestuff of Example 2 are dissolved in 3000 parts of water, the dye-bath is mixed with 40 parts of crystallized sodium sulfate, and 100 parts of a superpolyamide yarn (which is on the market under the registered name "Nylon") are dyed in this bath for 1 hour at 80–90° C. After rinsing and drying an extensively blue colored fiber is obtained.

Example 5

(1)	(Esterified with 1.1 mols. sulfonating agent [NH4-salt]).	Scarlet.
(2)	(Esterified with 1.2 mols. sulfonating agent [Na-salt]).	Red.
(3)	(Esterified with 1 mol. sulfonating agent [K-salt]).	Ruby red.
(4)	(Esterified with 1 mol. chlorosulfonic acid [NH4-salt]).	Red brown.
(5)	(Esterified with 1 mol. chlorosulfonic acid [NH4-salt]).	Red violet.
(6)	(Esterified with 1.3 mols. sulfonating agent [Na-salt]).	Violet.
(7)	(Esterified with 1.25 mols. chlorosulfonic acid [NH4-salt]).	Blue.
(8)	(Esterified with 1.2 mols. sulfonating agent [Na-salt]).	Greenish blue.
(9)	(Esterified with 1.2 mols. sulfonating agent [Na-salt]).	Ruby red.
(10)	(Esterified with 1.2 mols. sulfonating agent [Na-salt]).	Do.

What we claim is:

1. The mixtures of dyestuffs which in the free form correspond to the general formulas

and

wherein the proportion of the monoester (I) to the diester (II) is such that in 100 parts of dyestuff mixture the content of monoester (I) amounts to at least 50 per cent and the content of diester (II) amounts to at the most 25 per cent, in which formulas R_1 and R_2 stand for aromatic nuclei of the benzene series which are free from hydroxyl, carboxyl and sulfonic acid groups, R_1 containing a nitro group standing in para-position to the $-\text{N}=\text{N}-$ group, and the $-\text{N}=\text{N}-$ and the

groups in R_2 standing in 1:4-position to each other, the term "alkylene" in the foregoing formulae signifying an alkylene containing not more than 4 carbon atoms.

2. The mixtures of dyestuffs which in the free form correspond to the general formulas

and

wherein the proportion of the monoester (I) to the diester (II) is such that in 100 parts of dyestuff mixture the content of monoester (I) amounts to at least 50 per cent and the content of diester (II) amounts to at the most 25 per cent, in which formulas R_1 and R_2 stand for aromatic nuclei of the benzene series which are free from hydroxyl, carboxyl and sulfonic acid groups, R_1 containing a nitro group standing in para-position to the $-\text{N}=\text{N}-$ group, and the $-\text{N}=\text{N}-$ and the

groups in R_2 standing in 1:4-position to each other.

3. The mixtures of dyestuffs which in the free form correspond to the general formulas

and

15 wherein the proportion of the monoester (I) to the diester (II) is such that in 100 parts of dyestuff mixture the content of monoester (I) amounts to at least 50 per cent and the content of diester (II) amounts to at the most 25 per cent.

20 4. The mixtures of dyestuffs which in the free form correspond to the general formulas

and

wherein the proportion of the monoester (I) to the diester (II) is such that in 100 parts of dyestuff mixture the content of monoester (I) amounts to at least 50 per cent and the content of diester (II) amounts to at the most 25 per cent.

35 5. The mixtures of dyestuffs which in the free form correspond to the general formulas

and

55 wherein the proportion of the monoester (I) to the diester (II) is such that in 100 parts of dyestuff mixture the content of monoester (I) amounts to at least 50 per cent and the content of diester (II) amounts to at the most 25 per cent.

60 FRIEDRICH FELIX.
ALPHONSE HECKENDORN.
